MATHIAS BOIGNER, OF CHICAGO, ILLINOIS.

DESIGN FOR A BATH-TUB FOR BIRD-CAGES.

No. 39,869.

Specification for Design.

Patented March 9, 1909.

Application filed April 22, 1908. Serial No. 428,698. Term of patent 7 years.

To all whom it may concern:

Be it known that I, MATHIAS BOIGNER, citizen of the United States, residing at Chicago, in the county of Cook and State of Illinois, have invented a new, original, and ornamental Design for a Bath-Tub for Bird-Cages, of which the following is a specification, reference being had to the accompanying drawings, forming a part thereof.

This invention has for its object to provide a novel and ornamental design for a bath-tub adapted to be attached to a bird cage.

In the accompanying drawings illustrating my design: Figure —1— is a perspective view of a bath-tub for bird cages embodying the design. Figs. —2— and —3— are respectively a rear elevation and a top plan view of the same.

The bath-tub consists of a receptacle which is substantially rectangular, the rear and upper walls thereof being concavo-convex and the outer surfaces thereof ornamented with stars. In the front wall of the tub is an aperture through which access is had thereto.

I claim:

The ornamental design for a bathtub for bird cages as shown and described.

MATHIAS BOIGNER.
